REFRIGERATION

Hugo M. Ullstrand, Evansville, Ind., assignor to
Servel, Inc., New York, N. Y., a corporation of
Delaware

Application June 17, 1937, Serial No. 148,631
Renewed December 8, 1939

14 Claims. (Cl. 62—95)

My invention relates to refrigeration, and more particularly concerns cooling of a storage compartment of a refrigerator.

It is an object of my invention to provide an improvement for cooling a storage compartment of a refrigerator whereby food products may be preserved and maintained at a desired low temperature without dehydration thereof.

Another object of my invention is to increase the effective heat transfer surface of a cooling element in a storage compartment of a refrigerator with the aid of a heat transfer path or secondary cooling system arranged to provide a maximum amount of usable storage space in the compartment.

A further object of my invention is to increase the efficiency of a cooling element in a storage compartment of a refrigerator with the aid of a heat transfer system having solid shelves, whereby the solid shelves of the heat transfer system may be employed in place of ordinary perforated shelves for storing food products and at the same time aid the cooling element in maintaining the desired low temperature in the compartment.

The invention, together with the above and other objects and advantages thereof, will be more fully understood from the following description taken in conjunction with the accompanying drawings forming a part of this specification, and of which Fig. 1 diagrammatically illustrates a refrigeration system and a side vertical sectional view of a refrigerator embodying the invention; Fig. 2 is a horizontal sectional view of the refrigerator shown in Fig. 1 and taken on line 2—2 of Fig. 3; and Fig. 3 is a vertical sectional view taken on line 3—3 of Fig. 2.

Referring to Fig. 1, I have shown my invention embodied in a refrigerator comprising a cabinet 10 having an inner metal shell 11 arranged to be supported within an outer metal shell 12 and insulated therefrom with any suitable insulating material 14. The inner metal shell 11 defines a thermally insulated storage compartment 15 into which access may be had by a door 16 hinged to the front of the cabinet. Within the storage compartment 15 is arranged a cooling unit or evaporator 17 of a refrigeration system.

The refrigeration system or apparatus I have diagrammatically shown is of a uniform pressure absorption type, generally as described in Patent No. 2,037,782 to William R. Hainsworth, in which an auxiliary pressure equalizing gas is employed. In a system of this type a refrigerant fluid, such

as ammonia, is introduced through a conduit 18 into the cooling unit 17 and evaporates and diffuses therein into an inert gas, such as hydrogen, to produce a refrigerating effect. The resulting gas mixture of ammonia and hydrogen flows from cooling unit 17 through conduit 19, gas heat exchanger 20, and conduit 21 into an absorber 22.

In absorber 22 ammonia vapor is absorbed by a suitable absorbent, such as water, which enters through a conduit 23. The hydrogen, which is practically insoluble and weak in ammonia, is returned to the lower part of cooling unit 17 through conduit 24, gas heat exchanger 20, and conduit 25; and the enriched absorption liquid is conducted from absorber 22 through a conduit 26, liquid heat exchanger 27, and a conduit 28 into chamber 29 of a generator 30.

By heating generator 30, as by a gas burner 31, for example, liquid is raised by vapor-lift action through conduit 32 into the upper part of a stand-pipe 33. Liberated ammonia vapor entering stand-pipe 33 from conduit 32, and also the ammonia vapor expelled from solution in stand-pipe 33 and chamber 29, flows upward into an air-cooled condenser 35. Ammonia vapor is liquefied in condenser 35 and returned to cooling unit 17 through conduit 18 to complete the refrigerating cycle.

The weakened absorption liquid from which ammonia has been expelled is conducted from chamber 29 through conduit 36, liquid heat exchanger 27, and conduit 28 into the upper part of absorber 22. The heat liberated with absorption of ammonia vapor in absorber 22 is transferred to a cooling medium which flows through a coil 37 which is disposed about and in thermal relation with the absorber.

A vessel 38 is connected by conduit 39 to the lower part of condenser 35 and by conduit 40 to the gas circuit, as at absorber 22, for example, so that any hydrogen which may pass into the condenser can flow into the gas circuit. Ammonia vapor not liquefied in condenser 35 flows through conduit 39 to displace hydrogen in vessel 38 and force such hydrogen through conduit 40 into the gas circuit, so that the total pressure in the system is raised and an adequate condensing pressure is obtained to insure condensation of ammonia vapor in condenser 35.

In order to arrange the cooling unit 17 within the storage compartment 15, the rear insulated wall of the compartment is provided with an opening to receive a removable wall section 41. The conduits connecting the cooling unit 17 and

other parts of the refrigeration system extend through the removable wall section 41.

The cooling unit 17 includes an upper coil 42 and a lower coil 43. The coil 43 may be embedded in or otherwise suitably arranged in heat exchange relation with a shell 44 provided with a plurality of compartments to receive trays for freezing water and the like. The upper coil 42 is arranged with a plurality of cooling fins 45 for cooling air in the storage compartment 15.

Liquid ammonia entering the upper coil 42 through conduit 18 flows downward in counterflow to inert gas which flows upward and enters the lower coil 43 through conduit 25. Since the inert gas flows first through the lower coil 43 and then through the upper coil 42, the gas in the upper coil contains a greater amount of ammonia vapor than the gas in the lower coil. The partial pressure of ammonia vapor is therefore higher in coil 42 than in coil 43, and evaporation of liquid ammonia takes place at a higher temperature in the upper coil than in the lower coil.

In accordance with my invention, in order to increase the efficiency of the upper coil or cooling element 42 for cooling air in the storage compartment, I provide a heat transfer system which is preferably so constructed and arranged that the effective heat abstracting surface is increased without materially decreasing the usable storage space in the compartment. I accomplish this by providing a heat transfer system including a condensation portion 46, evaporation portions 47, and connecting conduits 48 and 49.

The condensation portion or condenser 46 serves as a part of a heat conductor and is in the form of a looped coil having straight portions and connecting bends, and is arranged in thermal exchange or heat conductive relation with the upper cooling element 42. The condenser 46 is preferably removably connected to the cooling element 42 and detachable therefrom by providing notches or recesses in the fins 45 to receive the straight portions of the condenser, as shown most clearly in Fig. 3, and rigidly securing the condenser in this position by straps 50 and 51 and connecting bolts 52. The upper straps 50 bear against the top of condenser 46 and the lower straps 51 bear against the bottom of coil 42, so that the condenser is in good thermal contact with the cooling fins 45.

The evaporation or heat abstracting portions 47 of the heat transfer path each comprise a pair of contacting metallic sheets 53 and 54 having a fluid passage formed therebetween. The top sheets 53 are substantially flat and connected in any suitable manner, as by welding or brazing, to the bottom sheets 54. The evaporation portions 47 form solid walls or shelves in the storage compartment and divide the latter into a plurality of separate compartments 15a, 15b, and 15c.

Although the solid shelves may be of such size that a space is provided between the edges of the shelves and the vertical walls of the compartment, I prefer to arrange the shelves in such a manner that no flow of air will take place between the separate compartments. To effectively seal the separate compartments from each other, a suitable gasket 55 may be provided about the periphery of each shelf 47, the gaskets being formed of a suitable resilient material, such as rubber, and bearing against the walls of the inner shell 11 at the shelf supports 56. When the door 16 is in its closed position, the inside of the door effectively bears against the portion of

the gaskets at the forward edges of the solid shelves. If desired, one or more of the separate compartments may be provided with an independent closure member. Such a separate closure member 60, which is hinged at its upper edge to the top shelf 47, is provided at the forward part of the middle compartment 15b, as shown in Fig. 1.

The condenser 46, evaporation members or solid shelves 47, and connecting conduits 48 and 49 form a closed fluid circuit which contains a suitable volatile fluid that evaporates within the solid shelves 47 and takes up heat thereby transmitting cooling effect and cooling the separate compartments. The system may be filled with liquid to a point above the top shelf 47, whereby the shelves constitute evaporation members of the flooded type with the bottom sheets 54 forming chambers for holding the volatile fluid in heat transfer relation to the shelves. The vapor flows upward through conduit 48 into the condenser 46, and the vapor is cooled and condensed by the upper cooling element 42. The condensate flows downward through conduit 49 and back into the solid shelves 47 where it is again evaporated. In the heat transfer path described, therefore, cooling effect is transmitted by the upper element 42 to the heat transfer system with such system conducting heat there-through to transmit cooling effect to the shelves 47 which form walls of the smaller compartments.

Since the low temperature cooling element 43 is normally operated below the freezing temperature of water, water vapor is condensed out of the air when air is permitted to flow in contact therewith. Under these conditions the condensed water vapor freezes and forms a coating of frost on the low temperature cooling element. Although the shell 44 in which the cooling element 43 is embedded has a limited heat transfer surface which may be employed to assist the higher temperature cooling element 42 for cooling air, the increased heat abstracting surface provided by the heat transfer path or system makes possible an arrangement for maintaining the separate storage compartments at a higher humidity. This may be effected by insulating the low temperature cooling element 43 with any suitable insulating material 57 to prevent removal of water vapor from air by this cooling element. The insulating material may be protected with a sheet metal cover 58 which may be secured to the removable wall section 41, as shown in Fig. 1.

When the low temperature cooling element 43 is insulated and the higher temperature cooling element 42 and heat transfer path are relied upon to maintain the storage compartment at a low temperature, the air is maintained at a higher humidity with less dehydration of the food products stored in the compartment. This is due to the fact that less water vapor is condensed from air flowing in contact with the solid shelves 47 and the higher temperature cooling element 42. When the relative humidity of air in the compartment is below a definite value, no removal of water vapor from air is effected because of the higher operating temperature of the cooling element 42.

Condensation of water vapor is almost unavoidable when a dew-point higher than 32° F. is desired. The condensed water vapor may be collected in any suitable manner in the storage compartment, or a drain system may be provided

ed for conducting water out of the compartment. Any condensate formed on the cooling element 42 and solid shelves 47 may be conducted to a common drain conduit which may be arranged to deliver the water to a heat rejecting part of the refrigeration system, such as the generator 30, for example, so that it will be heated and evaporated.

The above described arrangement for cooling air in the storage compartment is extremely flexible and may be readily modified to maintain the desired temperature and humidity conditions in any of the compartments. Although I prefer to insulate the low temperature cooling element 43 to maintain the upper compartment 15a at a humidity which will prevent dehydration of food products stored therein, the cooling element 43 may be employed without insulation when it is desired to maintain the upper compartment at a lower temperature to store certain food products therein.

By providing the solid refrigerated shelves 47 the middle and lower compartments 15b and 15c may be maintained at a higher humidity, even when the low temperature cooling element 43 is not insulated, so that dehydration of food products is substantially reduced. Since air in the middle compartment 15b flows in contact with both of the shelves 47 a greater amount of air cooling is effected in this compartment than in the lower compartment 15c where air flows in contact only with the lower refrigerated shelf. In addition to the different amount of air cooling that may be effected in the separate compartments, depending upon whether one or two walls of a separate compartment are refrigerated, the size of the different compartments may be varied to provide separate storage spaces capable of being maintained at different temperatures. Thus, by increasing or decreasing the size of the middle compartment 15b the temperature of this compartment may be increased or decreased.

In addition to the solid shelves 47 which are arranged to seal and prevent the flow of air from one compartment to another, additional perforated shelves 59 may be provided in the compartment. The solid shelves assist in supporting food products in the different compartments and provide a heat transfer path which does not materially reduce the usable storage space in the refrigerator. When the low temperature cooling element 43 is insulated so that no frost is formed thereon, defrosting of the cooling element is not necessary and the refrigeration system may be operated continuously under normal operating conditions. Since the heat transfer system is removably connected to the upper cooling element 42, it is insertable into the storage compartment from the front of the cabinet. This removable connection also permits removal of the cooling unit 17 through the opening in the rear insulated wall when the condenser 46 is disconnected from the upper cooling element 42, so that the heat transfer system may remain in its structural and cooling effect transmission relationship to the compartments of the storage space with removal of cooling unit 17.

Although I have shown and described my invention in connection with a particular type of refrigeration system, I do not wish to be limited thereto since any type of refrigeration system or systems may be employed to provide a low temperature cooling element and a high temperature cooling element in a storage compartment of a refrigerator. It will be understood by those

skilled in the art that various changes and modifications may be made and that certain features may be employed independently of others, without departing from the spirit and scope of my invention, as pointed out in the following claims.

What is claimed is:

1. In a refrigerator having a thermally insulated storage compartment and structure therein to support food products and the like, an absorption type refrigeration system having first and second cooling elements in which refrigerant fluid evaporates in the presence of an auxiliary agent, said first element being thermally segregated from said compartment and having a chamber for freezing ice and the like, said refrigerant fluid evaporating into auxiliary agent at a low temperature in said first cooling element and at a higher temperature in said second cooling element, and a system for heat transfer fluid having a heat rejecting portion in heat conductive relation with said second cooling element and a heat abstracting portion including said structure so as to minimize the amount of usable storage space occupied by said system in said compartment.
2. In a refrigerator having a thermally insulated storage compartment and one or more shelves therein to support food products and the like, an absorption type refrigeration system having first and second cooling elements in which refrigerant fluid evaporates in the presence of an auxiliary agent, said first element being thermally segregated from said compartment and having a chamber for freezing ice and the like, said refrigerant fluid evaporating into auxiliary agent at a low temperature in said first cooling element and at a higher temperature in said second cooling element, and a system for heat transfer fluid having a heat rejecting portion in heat conductive relation with said second cooling element and a heat abstracting portion in which heat transfer fluid is held in heat transfer relation to said shelf or said shelves so as to minimize the amount of usable storage space occupied by the system in said compartment.
3. In a refrigerator having a thermally insulated storage compartment provided with an opening, a door for closing the opening, an absorption type refrigeration system having first and second cooling elements in which refrigerant fluid evaporates in the presence of an auxiliary agent, said first element being thermally segregated from said compartment and having a chamber for freezing ice and the like, said refrigerant fluid evaporating into auxiliary agent at a low temperature in said first cooling element and at a higher temperature in said second cooling element, and a system for heat transfer fluid constructed and arranged to occupy a minimum amount of usable storage space in said compartment and having a heat rejecting portion and a heat abstracting portion, said system being insertable into said compartment through the opening, and said heat rejecting portion being in thermal exchange relation with said second cooling element and detachable from such thermal exchange relation.
4. In a refrigerator having a thermally insulated storage compartment and one or more shelves therein arranged to divide the compartment into a plurality of separate spaces between which flow of air is substantially prevented, an absorption type refrigeration system having first and second cooling elements in which refrigerant fluid evaporates in the presence of an auxiliary

agent, said first cooling element being thermally segregated from said compartment and having a chamber for freezing ice and the like, and said second cooling element being arranged to effect cooling of one of the separate spaces, said refrigerant fluid evaporating into auxiliary agent at a low temperature in said first cooling element and at a higher temperature in said second cooling element, and a system for heat transfer fluid including a heat rejecting portion in thermal exchange relation with said second cooling element and a heat abstracting portion including a chamber or chambers for holding heat transfer fluid in heat transfer relation to said shelf or shelves.

5. In a refrigerator having a thermally insulated storage compartment and one or more shelves therein to support food products and the like, an absorption type refrigeration system including upper and lower cooling elements connected for upward flow of auxiliary agent in series and downward flow of cooling agent in the presence of the auxiliary agent, said upper cooling element being arranged to extract heat from within said compartment and said lower cooling element being thermally segregated from said compartment and having a chamber for freezing ice and the like, and means to increase the rate at which heat is extracted from within said compartment by said upper cooling element including a system for heat transfer fluid having a heat rejecting portion in heat conductive relation with said upper cooling element and a heat abstracting portion in which heat transfer fluid is held in heat transfer relation to said shelf or shelves, whereby the amount of usable storage space occupied by said system in said compartment is minimized.

6. A refrigerator including a cabinet having a thermally insulated storage compartment, refrigeration apparatus having a low temperature cooling element for freezing water and a higher temperature cooling element for cooling air in said compartment, structure in said storage compartment for supporting food articles and the like, a chamber for holding a volatile fluid in heat transfer relation to said food supporting structure, and a heat transfer circuit for volatile fluid and including said chamber and having a portion in thermal exchange relation with said higher temperature cooling element.

7. A refrigerator as set forth in claim 6 in which said chamber forms a fluid passage in a shelf, and said shelf divides said compartment into a plurality of separate compartments.

8. A refrigerator as set forth in claim 6 in which said food supporting structure includes a plurality of shelves, each having a chamber forming a fluid passage and dividing said compartment into a plurality of separate compartments substantially without air flow therebetween.

9. In a refrigerator including a cabinet having a thermally insulated storage compartment and structure therein for supporting food products and the like, an absorption type refrigeration system having first and second cooling elements in which refrigerant fluid evaporates in the presence of an auxiliary agent, said first element being thermally segregated from said compartment and having a space for freezing ice and the like, said refrigerant fluid evaporating into auxiliary agent at a low temperature in said first cooling element and at a higher temperature in said second cooling element, a first chamber for holding

5 a volatile fluid in heat transfer relation with said food supporting structure, and a second chamber in heat conductive relation with said second cooling element and connected to said first chamber, said first and second chambers constituting evaporation and condensation portions, respectively, of a circuit for the volatile fluid.

10. In a refrigerator including a cabinet provided with an inner liner member forming a food storage compartment having an opening at the front of the cabinet, the top and bottom of the liner member being spaced apart substantially the height of the rear and lateral side walls thereof, refrigeration apparatus including a cooling element in said compartment, the cooling element having a chamber adapted to receive matter to be refrigerated, a door for the cabinet opening for inserting and removing food products and the like into and from the food compartment and also affording access to the chamber of the cooling element, a shelf in the compartment having the peripheral edges thereof at or adjacent to the rear and lateral side walls of the liner member and adapted to support food products and the like normally maintained above freezing temperature, and means to utilize the shelf to abstract heat from the storage compartment, the last-mentioned means being constructed and arranged to occupy a minimum amount of usable storage space and including a first chamber within the liner member for holding a volatile fluid in heat transfer relation to the shelf, a second chamber in heat conductive relation with the cooling element, and conduit means connecting the first and second chamber having a vertically extending portion adjacent a wall of the liner member, the first and second chambers constituting evaporation and condensation portions, respectively, of a circuit for the volatile fluid.

11. In a refrigerator including a cabinet having a storage space and a solid shelf in said space to divide the latter into compartments between which circulation of air is restricted, refrigeration apparatus including a cooling element in one of said compartments, food supporting structure in another of said compartments, a first chamber for holding a volatile fluid in heat transfer relation to said food supporting structure, a second chamber detachably connected in heat conductive relation with said cooling element and connected to said first chamber, said first and second chambers constituting evaporation and condensation portions, respectively, of a circuit for the volatile fluid, said cabinet having a common door for gaining access to both of said compartments, and said circuit including said evaporation and condensation portions being removable as a single unit through said door from said storage space when said second chamber or condensation portion is detached from its heat conductive relation with said cooling element.

12. A refrigerator including a cabinet having a thermally insulated food storage space provided with an inner liner, the food storage space being open at the front of the cabinet, a plurality of horizontally disposed walls in said space forming shelves for supporting food articles and the like, one of the walls dividing the space into compartments between which circulation of air is substantially prevented, the top, bottom, rear and lateral sides of the liner forming walls of the compartments, refrigeration apparatus including evaporator structure in one of the com-

partments, the evaporator structure having a chamber adapted to receive matter to be refrigerated, a door for the cabinet opening for inserting and removing food products and the like into and from said one compartment and also affording access to the chamber of the evaporator structure, a heat transfer path including a portion in heat transmitting relation to one of the walls of said other compartment and transmitting cooling effect thereto, and means serving as a heat conductor in heat transmitting relation with said portion for transmitting cooling effect thereto, said heat conductor means including a part in heat conductive relation with the evaporator structure whereby the evaporator structure transmits cooling effect to said heat conductor means when in functioning relationship, said part of said heat conductor means being detachable from its heat conductive relation with the evaporator structure whereby the latter is removable from the cabinet, and said portion and said heat conductor means of the heat transfer path being arranged so that they may remain in their structural and cooling effect transmission relationship to the other compartment upon removal of the said evaporator structure.

13. A refrigerator including a cabinet having a thermally insulated food storage space provided with an inner liner, the food storage space being open at the front of the cabinet, a plurality of horizontally disposed walls in said space forming shelves for supporting food articles and the like, one of the walls dividing the space into compartments between which circulation of air is substantially prevented, the top, bottom, rear and lateral sides of the liner forming walls of said compartments, refrigeration apparatus including evaporator structure in one of the compartments, the evaporator structure having a chamber adapted to receive matter to be refrigerated, a door for the cabinet opening for inserting and removing food products and the like into and from said one compartment and also

affording access to the chamber of the evaporator structure, a first chamber for holding a volatile fluid in heat transfer relation to one of the walls of said other compartment, a second chamber connected to said first chamber, said first and second chambers constituting evaporation and condensation portions, respectively, of a circuit for the volatile fluid, said second chamber or condensation portion being in heat conductive relation with the evaporator structure whereby the evaporator structure transmits cooling effect to said condensation portion when in functioning relationship, said condensation portion or first chamber being detachable from its heat conductive relation with the evaporator structure whereby the latter is removable from the cabinet, and said circuit for the volatile fluid including said first and second chambers being arranged so that they may remain in their structural and cooling effect transmission relationship to said other compartment upon removal of the evaporator structure.

14. In a refrigerator including a cabinet having an inner liner forming a storage space provided with a front opening, a closure for the opening, and a solid shelf to divide said space into compartments between which circulation of air is restricted, refrigeration apparatus including a cooling element in one of said compartments, a heat transfer circuit containing a volatile fluid and including a heat rejecting portion in said one compartment in heat conductive relation with said cooling element, a heat abstracting portion in said other compartment, and conduit means connecting said heat rejecting portion and said heat abstracting portion, said conduit means being disposed in said space and passing through the plane of said solid shelf, and said heat transfer circuit being insertable and removable as a unit into and out of said space through the front opening.

HUGO M. ULLSTRAND.
